LUBRICATING COMPOSITION

Carl F. Prutton, Cleveland, and Albert K. Smith, Shaker Heights, Ohio, assignors, by mesne assignments, to The Lubri-Zol Development Corporation, Cleveland, Ohio, a corporation of Delaware

No Drawing. Application December 19, 1940,
Serial No. 370,838

4 Claims. (Cl. 252—48)

This invention relates, as indicated, to lubricating compositions and more particularly, to compositions for use in connection with the lubrication of the working parts of internal combustion engines, motor vehicles, etc. and it is among the objects of the invention to provide compositions obviating the disadvantages of the usual petroleum oils.

It has been explained by specialists in this particular field of the art that a lubricant employed for the purpose of reducing friction between relatively movable metallic parts functions in two ways commonly referred to as "thick-film" lubrication and "thin-film" lubrication.

In "thick-film" lubrication the bearing surfaces are completely separated by a relatively thick continuous film of the lubricating composition employed. When friction between the moving parts is measured in this case, the results obtained are independent of all factors except pressure, speed and the viscosity of the lubricating composition. A single curve representing all data may be found by plotting the coefficient of friction against a particular function consisting of the product of the viscosity of the lubricating composition and the speed of relative movement of the parts divided by the pressure per unit area of the bearing surface, as long as the value of such function is greater than a definite amount. At this minimum point, reduction of viscosity or speed or an increase in the pressure results in a breaking down of the film of lubricant. Although the value of the coefficient of friction is lowest at the point at which the film is about to break down, the increase in the coefficient for higher viscosity and speed or lower pressure is relatively slight. The conditions resulting in "thick-film" lubrication are, therefore, those which result in low friction.

For pressures sufficiently great or for correspondingly low values of viscosity or speed, the film of lubricant, as above indicated, is broken down and if it is not entirely destroyed, the metallic bearing surfaces are still affected to some extent, at least by the presence of the lubricating composition. This condition is commonly referred to as "thin-film" lubrication.

When one of the bearing surfaces is a metal such as bronze or babbitt, seizure does not take place at once but the coefficient of friction increases rapidly to abnormally high values with each slight further increase in pressure or decrease in viscosity or speed. For a given set of bearings the data obtained for "thin-film" lubrication may be approximately coordinated into a single curve but only on plotting coefficient of friction against the product of viscosity and speed divided by the square root of the pressure.

If both bearing surfaces are of steel, seizure or scoring will result almost immediately upon failure of "thick-film" lubrication when a pure mineral oil is the sole lubricating composition employed.

It is among the objects of our invention to provide a lubricating composition which may be employed to reduce the friction between relatively movable metallic surfaces under pressures and other factors which result in what has been above explained as "thick-film" lubrication and a composition which may be employed for such "thin-film" lubrication and without a material increase in the coefficient of friction between the parts over that found during "thick-film" lubrication.

Other objects of our invention will appear as the description proceeds.

To the accomplishment of the foregoing and related ends, said invention, then, consists of the means hereinafter fully described and particularly pointed out in the claims.

The following description sets forth in detail one approved combination of ingredients embodying our invention, such disclosed means constituting, however, but one of various forms in which the principle of the invention may be used.

Broadly stated, this invention comprises incorporating certain forms of halogenated carbon compounds with certain types of oil bases. More specifically, the invention comprises incorporating a halogenated carbon compound with a sulphur treated oil base.

By the term "sulphur treated oil" as employed in this description, is meant any suitable oil base which has been treated with sulphur, for example, the composition produced by heating sulphur with a fixed oil, such as lard oil or fish oil; or to which sulphur or a sulphur compound, (e. g. di-phenyl di-sulphide) has been added, so that a certain amount of sulphur is present in active or loosely combined form. It has been found that a suitable oil base containing from 0.50% to 2.50% of sulphur in active or loosely combined form is best suited for use in a composition according to the present invention. These percentages are not to be construed, however, as limitations but merely an indication of the range of sulphur in the form defined for optimum results.

Examples of other sulphur compounds which may be added to an oil base to obtain a sulphur treated oil are the products obtained by the reaction of an organic halogen compound with a sulphur compound, such as for example the inorganic sulphides and polysulphides, resulting in the complete or partial substitution of a sulphur-bearing radicle for the halogen. Examples of

such materials are the reaction products of sodium sulphide, sodium polysulphide, sodium thiocyanate, or potassium xanthate with aralkyl chlorides such as:

Benzyl chloride
Chlor-benzyl chlorides
Xylyl chloride
Chlor-xylyl chlorides

or with alkyl chlorides such as:

Lauryl chloride
Cetyl chloride
Chlorinated petroleum naphtha
Chlorinated petroleum wax

or with cyclo-aliphatic chlorides such as:

Cyclohexyl-methyl chloride
Naphthyl chloride

The halogenated carbon compounds which are added to sulphur-treated oil bases, as above defined, in accordance with the present invention, are preferably halogenated or more specifically chlorinated carbon ring compounds and preferably oxygen-containing halogenated, or more specifically, chlorinated carbon ring compounds.

The halogenated oxygen-containing carbon ring compounds added to a sulphur treated oil base are, as above indicated, preferably of the chlorinated species and particularly the following compounds have been found to produce very satisfactory results, viz: halogenated or more specifically, chlorinated oxygen-containing substituted benzene compounds such as:

Chlorinated phenols
Chlorinated cresols
Chlorinated diphenylether
Chlorinated methyl salicylate

halogenated substituted di-phenyl such as:

Chlorinated P-phenyl phenol
Chlorinated di-xenyl ether

chlorinated substituted naphthalenes such as:

Chlorinated naphthols;

as well as the aromatic ethers, phenols, acids, the esters and the aldehydes.

For many purposes it is particularly advantageous to use a halogenated oxygen-containing carbon-ring compound which contains a carbonyl

(>C=O)

radicle such as the cyclo-aliphatic and aromatic aldehydes, amides, ketones, acids, esters and salts, thio-acids and esters and salts of thio-acids.

Specific examples of preferred compounds of which the halogen-bearing derivatives may be used for our purpose are as follows:

Aldehydes:

Benzaldehyde
Furfural
Phenyl acetaldehyde
Lauryl benzaldehyde

Amides:

Acetanilide
Anilides of naphthenic acids
Benzamide
Benzanilide
Lauryl benzamides
Lauryl benzanilides
Naphthyl benzamides
Naphthyl benzanilides
Stearanilide

Ketones:

Acetophenone
Anthraquinone
Benzaphenone
Benzil
Benzoin
Butyl benzophenones
Camphor
Cyclohexanone
Di(methyl-phenyl) ketone
Dinaphthyl ketone
Dixenyl ketone
Furil
Furoin
Lauryl benzophenones
Methyl benzophenones
Methyl xenyl ketone
Naphthyl benzene
Naphthyl diphenyls
Naphthyl naphthalenes
Stearoyl benzene
Stearoyl naphthalenes
Stearoyl diphenyls
Stearoyl diphenyl ethers
Phenyl naphthyl ketone

Acids:

Azobenzoic acid
Azolauryl benzoic acid
Benzene sulphonic acid
Benzoic acid
Cinnamic acid
Diphenyl acetic acid
Ethyl salicylic acid
Mercapto benzoic acid
Mercapto lauryl benzoic acids
Mercapto rosolic acid
Lauryl benzene sulfonic acids
Lauryl benzoic acids
Lauryl phenyl acetic acids
Lauryl phenyl propionic acids
Lauryl salicylic acids
Lauryl thiobenzoic acids
Lauryl toluic acids
Naphthyl benzene sulfonic acids
Naphthyl benzoic acids
Naphthyl phenyl acetic acids
Naphthyl salicylic acids
Naphthyl thiobenzoic acids
Naphthyl toluic acids
Phenoxyphenyl stearic acid
Phenyl acetic acid
Phenyl mercapto stearic acid
Phenyl propionic acid
Phenyl stearic acid
Stearoyl benzene sulfonic acid
Stearoyl benzoic acids
Stearoyl phenyl acetic acids
Stearoyl salicylic acids
Stearoyl thiobenzoic acids
Stearoyl toluic acids
Thiobenzoic acid
Toluic acid

Esters:

65 Amyl salicylate
Benzyl acetate
Benzyl benzoate
Benzyl stearate
Butyl azobenzoate
70 Butyl esters of pyrrole carboxylic acid
Butyl esters of thiophene carboxylic acid
Butyl benzoate
Butyl thio-benzoate
75 Butyl ester of mercapto rosolic acid
Butyl ester of phenyl acetic acid

Esters—Continued

Butyl ester of phenyl stearic acid
 Butyl furoate
 Butyl mercapto benzoate
 Butyl toluate
 Dilauryl phthalate
 Dibutyl phthalate
 Esters of cinnamic acid
 Esters of diphenyl acetic acid
 Ethyl ester of phenyl acetic acid
 Esters of ethyl salicylic acid
 Ethyl toluate
 Esters of phenyl mercapto stearic acid
 Esters of phenyl propionic acid
 Lauryl benzoate
 Lauryl salicylate
 Lauryl toluate
 Lauryl ester of phenyl acetic acid
 Methyl ester of lauryl salicylic acid
 Methyl ester of phenyl stearic acid
 Methyl ester of phenyl mercapto stearic acid
 Methyl ester of naphthenyl benzoic acid
 Methyl ester of stearoyl benzoic acid
 Lauryl ester of phenyl propionic acid
 Methyl toluate
 Phenyl acetate
 Phenyl benzoate
 Phenyl stearate
 Salts of organic bases:
 Aniline oleate
 Aniline stearate
 Benzylamine stearate
 Dilauryl amine benzoate
 Dilauryl amine salt of phenyl stearic acid
 Lauryl-pyridine stearate
 Lauryl-quinoline stearate
 N-lauryl aniline oleate
 N-lauryl aniline stearate
 N-lauryl aniline mercapto stearate
 N-lauryl aniline naphthenate
 N-lauryl naphthylamine stearate
 N-naphthenyl aniline stearate
 N-naphthenyl butylamine benzoate

Salts of inorganic bases:

Aluminum phenyl mercaptostearate
 Aluminum phenyl stearate
 Barium phenyl stearate
 Calcium lauryl thiobenzoate
 Calcium naphthenyl benzoate
 Calcium naphthenyl thiobenzoate
 Calcium phenyl mercapto stearate
 Calcium phenyl stearate
 Calcium phenyl thiostearate
 Calcium stearoyl benzoate
 Calcium stearoyl thiobenzoate
 Sodium phenyl mercaptostearate
 Sodium phenyl stearate
 Zinc naphthenyl benzoate

The "halogen derivatives" referred to above may be prepared by (a) directly halogenating (e. g. chlorinating) the compounds listed, or by (b) treating the compounds listed with a halogenating agent (e. g. SOCl_2 , PCl_5 , etc.) or by (c) the reaction of halogen-containing intermediates. For example, halogen derivatives of methyl salicylate may be prepared by

(a) direct halogenation of methyl salicylate, e. g. by passing chlorine through methyl salicylate preferably in the presence of a catalyst such as iodine, PCl_3 , iron, etc., or by
 (b) treating methyl salicylate with PCl_5 , or by
 (c) esterifying chlor-salicylic acid with methyl alcohol.

By the term "naphthenyl" as used herein, we mean the radicles which have the structure

5 (in which R is a cyclo-aliphatic group, or an alkyl-cyclo-aliphatic group) which result from naphthenic acids by the removal of the hydroxyl group. For example, "naphthenyl" chloride 10 would be the acid chloride derived from a naphthenic acid and "naphthenyl benzene" would be the compound resulting from the Friedel-Crafts condensation of naphthenyl chloride with benzene.

15 Since generally the addition of compounds of the class including the above enumerated reduce the viscosity of the oil base to which the same are added, if a large percentage of such compounds are added, there will be a tendency to 20 destroy "thick-film" lubrication because of such reduction in viscosity. If an excessive quantity of such compounds are added, all of the lubrication will then be of the "thin-film" type and therefore produce a decided increase in the amount of friction developed.

25 Optimum results are obtained by using minimum quantities of these halogenated compounds so that their beneficial effect in the region of "thin-film" lubrication will not be over-shadowed 30 by their detrimental effect in the region of "thick-film" lubrication.

Our invention contemplates incorporating with a sulphur treated oil base a total of less than 20% of at least one halogenated oxygen containing 35 carbon ring compound of the enumerated class.

35 The optimum amount of the halogenated compound to be employed will depend largely upon the halogen content of the particular compound, its physical characteristics and especially its effect 40 on the viscosity of the oil to which it is added. The particular use for which the lubricant is intended is also a governing factor in determining the amount of the compound to be added.

For the purpose of lubricating and reducing the 45 friction between the relatively movable parts of an internal combustion engine such as crank case bearings, piston and cylinder surfaces, as well as piston rings and valves, a composition according to our invention comprises a large proportion of 50 a sulphur treated oil base and concentrations of from one-half to two per cent of halogenated compounds of the above class containing from 50% to 25% of chlorine. If the valve structure of the engine is to be lubricated separately from 55 the remainder of the mechanism or by means acting in an auxiliary fashion, the composition for such purposes will preferably contain a larger amount of such halogenated compounds, i. e., from 2% to 10%.

60 The limit of the amount of the halogenated compounds which may be added to a sulphur treated oil base and which will produce improved results depends, as above indicated, upon the reduction in viscosity of the composition caused by 65 the addition of such compounds. Certain of the more viscous compounds, for example, dimethyl dichlor benzophenone, may be added in amounts exceeding 10% without causing too great a reduction of viscosity. In any event, the resultant 70 composition will have inferior lubricating properties if the loss of viscosity is too great as will result from the use of more than 20% of halogenated compounds of any type.

75 It has been found that for optimum results a certain relationship should be maintained be-

tween the amount of chlorine and the amount of sulphur, when the halogenated compounds of the above class are added to a sulphur treated oil. It has been found that to an oil base having a low content of sulphur in active or loosely combined form, halogenated compounds should be added in correspondingly low concentrations for best results.

When the halogenated compounds of the above class added to the sulphur treated oil base are of the closed ring type in contradistinction to the open chain type, certain advantages are obtained which may be briefly explained as follows:

In case of oil in actual use in machinery of any kind and particularly in the crank case of internal combustion engines, moisture is usually present to some extent and due to condensation may even accumulate to form a separate layer. There is usually sufficient water present, therefore, for hydrolysis to take place, particularly when the addition of a chlorinated compound is made to the extent of only a few percent.

Experiments have shown that when compounds which readily hydrolyze, such as chlorinated open chain compounds, are added to the sulphur treated oil base, hydrolysis may take place to such an extent that the metal parts of any machine being lubricated will be seriously attacked and corroded by the acid generated. On the other hand, the addition of chlorinated carbon ring compounds of the above enumerated class does not cause corrosion, particularly when such compounds are of the type in which the halogen is directly attached to a benzenoid ring.

The oil base of our lubricating compositions is a lubricating oil of the type best suited for the particular use for which the ultimate composition is designed. When the lubricating compositions of our invention are designed for the lubrication of automobiles, the oil base will of course preferably consist of a refined mineral lubricating oil of lubricating viscosity for the particular point of application. In other words, the conventional gear oil may be used for the lubrication of gears, for example, mineral oil having a viscosity range of from an S. A. E. 80 to an S. A. E. 140. Generally a lighter, more highly refined oil may be used in the crank case, such as a motor oil having a viscosity range of from an S. A. E. 10 to an S. A. E. 50.

This invention is applicable to lubricating compositions in which the base may consist either entirely or in part of synthetic oils, hydrogenated oils, and volatilized oils.

The oil base may also desirably contain other well known constituents such as those which improve the oiliness, pour point, cold test, and oxidation properties, etc., of the oil. In general compositions of our invention may be employed with any commercially available addition agents for the above defined purposes since they are generally compatible with the same in the amounts usually used.

The composition comprising our invention has certain advantages when used as a lubricant of which the following may be mentioned:

First: By the use of this composition it is possible to extend the pressure range between the bearing surfaces because of the reduced tendency for bearing surfaces so lubricated to become scored or to seize at higher pressures than are allowable with ordinary lubricants.

Second: The friction between the bearing surfaces is reduced, especially in the higher pres-

sure range below that obtained with ordinary lubricants.

When used in conjunction with a hydrocarbon lubricating oil, it is obvious that, generally, only such amounts of the addition agent may be included as are soluble in the specified amount of oil. By the term "soluble," as herein used, it is intended to indicate the ability to form not only true solutions but also any form of substantially permanently homogeneous composition when incorporated in mineral oil. With most of the compounds there is usually little difficulty, especially if the incorporation is effected in the manner described in Cornell Patent No. 2,042,880, and since quite small percentages often give remarkably improved results, it is seldom of extreme importance that the addition agents be oil-soluble in all proportions.

The addition agents above enumerated for use in my compounded lubricants include certain ones which may be found to at least partially decompose under conditions of extreme stress such as the very high temperature encountered in certain classes of use, while others are quite stable even under such extreme conditions.

The use for which the lubricant is designed therefore determines the particular type of addition agent to be selected. A certain amount of decomposition, which proceeds at a relatively slow rate, is usually not harmful. Care should be exercised, however, to select for a particular set of operating conditions, an addition agent which in the oil base used will not decompose under such operating conditions except at a low rate.

By the term "stable" as used herein in describing the addition agents is meant the characteristics of the addition agents which enables them to resist decomposition in the oil under the condition of use for which the lubricating composition is designed.

In view of the particular uses for which my compounded lubricants are intended, it is apparent that of the materials included in the foregoing enumeration of the addition agents which may be employed, those which are readily oil-soluble are the ones preferred for use. When these compounded oils are designed for use under conditions where high temperatures are usually encountered, the addition agents should be stable at elevated temperatures. For use in crankcase lubricants for internal combustion engines, they should preferably be stable to the extent where there will be substantially no decomposition, when the lubricating composition is exposed to temperatures up to 250° F.

With regard to the use of sulphur treated oil in combination with halogenated compounds, it should be noted that for sufficiently desirable results, the major proportion of the ultimate composition need not consist entirely of sulphur-treated oil, but a suitable oil base such as mineral oil may have added thereto minor quantities or proportions of either a sulphur treated oil or a sulphur compound, and a halogenated compound.

This application is a continuation in part of copending application Serial No. 744,600, filed September 17, 1934, which was in turn a continuation of application Serial No. 649,734, filed December 31, 1932, now Patent No. 2,213,532, and application Serial No. 170,500, filed October 22, 1937, now Patent No. 2,204,620 (a division of application Serial No. 737,070, filed July 26, 1934). Other modes of applying the principle of the

invention may be employed, change being made as regards the details described, provided the features stated in any of the following claims or the equivalent of such be employed.

We therefore particularly point out and distinctly claim as our invention:

1. A lubricating composition comprising a major proportion of mineral lubricating oil and minor amounts of both a sulphur treated oil and a stable oil-soluble halogen bearing organic ring compound containing a carbonyl radicle.

2. A lubricating composition comprising a major proportion of mineral lubricating oil and

minor amounts of both a sulphur treated oil and a stable oil-soluble halogen bearing aromatic compound containing a carbonyl radicle.

3. A lubricating composition comprising a major proportion of mineral oil and minor amounts of both a sulphur treated oil and a halogen-bearing methyl salicylate.

4. A lubricating composition comprising a major proportion of mineral oil and minor amounts of both a sulphur treated oil and chlor-methyl salicylate.

CARL F. PRUTTON.
ALBERT K. SMITH.
